THERMOSTATIC ARRANGEMENT FOR GAS RANGES

Filed Aug. 22, 1929 2 Sheets-Sheet 2

UNITED STATES PATENT OFFICE

ARTHUR STOCKSTROM AND ALMER H. BRODBECK, OF ST. LOUIS, MISSOURI, ASSIGNEES
TO AMERICAN STOVE COMPANY, OF ST. LOUIS, MISSOURI, A CORPORATION OF NEW JERSEY

THERMOSTATIC ARRANGEMENT FOR GAS RANGES

Application filed August 22, 1929. Serial No. 387,729.

This invention relates to improvements in thermostatic arrangement for gas ranges and the primary object of this improvement is to so construct a range that the thermostat is concealed whereby a structure is produced so that when not in use there is little evidence that it is a range. 5

A further object of the invention is the production of a gas range so constructed that 10 when it is not in use the burner top is completely concealed and also the thermostatic arrangement is likewise concealed, whereby the range has the appearance of a piece of furniture, thus enabling the range to be used 15 in small apartments, dinettes, etc. without exposing any of its mechanism.

A further object of the improvement is in so constructing a range that there is produced a thermostatic compartment for concealing the thermostat. 20

A further object of the improvement is the production of a range that embodies a baking and a broiling oven and at one side thereof a vertical thermostatic containing compartment and a burner top extending over the said ovens and compartment and providing means for concealing the burner top and also the thermostatic compartment, whereby a range is produced that conceals 30 all of its mechanism when not in use.

A further object of the present improvement is to construct a range in the manner above described and provide a vertical narrow compartment for the thermostat and at the same time enable the thermostatic mechanism and the thermostat itself to be disconnected from the manifolds and when disconnected by swinging the thermostatic mechanism and the thermostat the complete mechanism and thermostat can be removed through the narrow vertical compartment from the range for repairing, and whereby the thermostatic mechanism and the thermostatic member can be applied to the range 45 through the same opening.

Further objects of the invention will appear from the following description.

In the drawings: 50 Figure 1 is a perspective view of our im-

proved range, a part of the range being broken away.

Figure 2 is a perspective view of our improved range, the concealing cover being raised for operation and the outer wall of the 55 thermostatic compartment broken away.

Figure 3 is a detached perspective vertical sectional view taken through the outer wall of the thermostatic compartment.

Figure 4 is a detached view showing the 60 arrangement of the gas manifold and the manner of connecting the valve housings with the said manifold.

Our improved range comprises a baking oven 1 and below it a broiling oven 2 which 65 may be of the ordinary construction and one feature of the present improvement is the provision of a thermostatic compartment 3 which contains the thermostatic housing 4 that has connected with it a thermostatic member 5 that extends into the upper front portion of the baking oven 1. The thermostatic housing 4 contains the usual or other thermostatic mechanism (not shown) that is adapted to be operated by the expansion and 70 contraction of the thermostatic member 5. This thermostatic housing includes the usual valve for controlling the flow of gas through the housing that is controlled by the thermostatic member, the regulating wheel and intervening mechanism well known to those skilled in this art, and not shown herein. The thermostatic housing 4 carries a regulating wheel 6 that has its shaft (not shown) 75 extending into the housing 4 that cooperates with the said mechanism within the housing. As here shown this compartment 3 is a narrow vertical compartment and the outer end of this compartment is closed by a plate 7. This plate is detachable for the purpose of 80 enabling the thermostat to be applied to the range, the housing being held in position by a suitable bolt 8 or other member, and this plate is made removable also to enable the thermostatic housing to be removed from the range for the purpose of repairing. In the 85 construction shown this outer wall or plate 7 is provided with means for removably attaching it in place. The means here shown consists in providing one end (the lower end) 90

95

100

8 with an inwardly and downwardly extending lip 9 which is made essentially L-shaped and this lip or lips pass through a vertical opening 10 that is formed in the lower edge 11 of the surrounding wall 12 of the range. 5 In this construction as here shown, this lower edge is bent preferably in the manner shown though it may be bent in other forms, and the lip 9 be bent to cooperate with its edge. The 10 upper portion of the wall 7 is provided with a handle 13 that passes through the said wall and has attached to it a latch 14, the lip 15 of the latch adapted to turn into an opening 16 of the inwardly L-shaped bent upper wall 17 of the said surrounding portion 12. By 15 means of this construction the said wall 7 can be fastened in position or detached by operating the handle 13 to either cause its latch 15 to engage with the wall 17 or to be 20 disengaged therefrom.

The thermostat, as is well understood by those skilled in the art, is to control the flow of gas to the burner 18' that provides heat for the oven 1 and the broiler 2. Gas for this 25 burner therefore passes through the housing 4 to the burner 18' and in passing through the housing it is controlled by the mechanism in the housing as is also well understood by those skilled in this art. The gas is conveyed 30 from the housing through a pipe 19 the lower end 20 of which passes to the burner 18' through a mixing chamber 21 which contains the usual air regulating shutter 22. Gas flows to the upper portion of the housing 4 35 through a pipe 23 that has one end connected with the housing 4 and its opposite end 24 connected with the manifold 25 located below the top plate 26. For the purpose of controlling the flow of gas from the manifold 40 25 to the pipe 23 its upper end 24 is made in the form of a valve housing that contains a valve (not shown) that is operated by a handle 27. The object of the valve control by the handle 27 is to cut off the gas flowing to 45 the thermostat from the manifold 25 or to permit gas to flow from the manifold 25 to the housing 4, and as previously stated herein, then the amount of gas flowing to the pipe 19 is controlled by the thermostat and 50 this in turn is controlled by the amount of heat within the oven 1. The adjustable wheel 6 before described, is set to feed sufficient gas to maintain the oven 1 at a predetermined heat, all of which is also well understood by those skilled in this art, and further description is unnecessary in this application.

The manifold 25 as stated, extends under the top plate 26 and its rear end 28 passes 60 to the ordinary source which is not here shown. The plurality of handles 29 located under the top plate 26 control the gas that flows to the burners (not shown) under the top plate, which does not need further description in this application. The top plate 65

26 has its front edge 30 extending over the handles 29 and the top plate curves downwardly and outwardly at opposite ends as at 31 and lays above the upper portion of the oven 1. The ordinary drip pan 32 is located under the burner mechanism that has been referred to. 70

In connection with this top 26 we provide a cover 33 that has its lower edge connected with the top plate in any desired manner so that the cover can swing upward in the position shown in Figure 2 or swing downward into the position shown in Figure 1, whereby the top plate and its burners and mechanism can be concealed when not in use and can be made accessible by raising the top when they are being used. We have not shown any particular manner of attaching this cover to the top plate in order to enable it to be operated as described since that may be varied without departing from the scope of the invention which it is the object of this application to protect. Also the outer or upper edge 33 of the flanges 34 are provided with extensions 35 and the end wall 36 of this cover is made wider than the flanges 34, and the extensions 35 are curved as shown for the purpose of fitting the curved portions 31 of the top plate, whereby all of the mechanism of the range is concealed. 85

It will be understood that the thermostatic compartment 3 may have an inner wall 37, or this wall 37 may be omitted. When the inner wall is provided its upper edge is below the thermostatic member 5 whereby the housing 4 and the thermostatic member can be applied to the range or can be detached from the range. Of course it will be also understood that the ends of the pipes 19 and 23 which are connected with the housing 4 100 will have any form of nipples (not shown) for detachably connecting the pipes with the housing 4. 105

For the purpose of enabling the regulating wheel 6 to be operable from the outside 110 of the range we provide the wall 7 with an opening 38 through which a part of the regulating wheel 6 extends just sufficiently to enable it to be operated and to expose one or more designations (not shown) indicating the predetermined heat within the oven. In the form here shown we preferably slightly depress the wall of this opening. It will be understood that this may be varied so long as the object of it is accomplished. 115

We have explained this improvement in considerable detail but we wish it understood that variations may be made in the construction without departing from the spirit of the invention so long as the variations are within a liberal interpretation of the appended claims. 120

Having thus described our invention what we claim and desire to secure by Letters Patent is: 125

1. A gas range comprising a housing including an oven and a narrow vertically arranged compartment located at one side of the oven, a burner top located above the oven, a manifold extending along the burner top to supply gas to its burners, said burners provided with handles for controlling the gas, a swinging top adapted to enclose the burner top, manifold, burners and handles when not in use, a thermostatic housing located within the vertically arranged compartment, a burner for the oven, the thermostatic housing having gas inlets and outlets, the inlet communicating with the said manifold and the outlet communicating with the oven burner, means for regulating the thermostat, that part of the range housing enclosing the thermostatic housing having an opening through which the regulating member is exposed, whereby the parts operate for the purpose set forth.

2. A gas range comprising a housing including an oven and also a vertically arranged compartment at one side of the oven, a burner for the oven, a thermostatic housing located within the said compartment and provided with a thermostatic member projecting within the oven, the said compartment provided with an outer wall attachable and detachable from the range housing for the purpose specified, said detachable wall having an opening, and a thermostatic housing provided with a regulating member projecting through the said opening, gas inlets and outlets communicating with the thermostatic housing, the gas outlet communicating with the burner and the gas inlet communicating with a manifold.

In testimony whereof we hereunto affix our signatures.

ARTHUR STOCKSTROM.
ALMER H. BRODBECK.
